HOOD CAPPING CLOSURE DISK

Wilbur L. Wright and Lee D. Pierce, Fulton, N. Y.,
assignors to Oswego Falls Corporation, Fulton,
N. Y., a corporation of New York

Application May 25, 1932, Serial No. 613,534

5 Claims. (Cl. 215—38)

This invention relates to dished disks of paper or other flexible suitable sheet material for shaping to hood cap form on bottle heads; and the objects and nature of the invention will be understood by those skilled in the art in light of the following description of the accompanying drawing that illustrates the preferred mechanical expression or embodiment of the invention from among other forms and constructions with-
10 in the spirit and scope thereof.

An object of the invention is to produce, as a new article of manufacture, a non-metallic more or less flexible sheet material approximately flat dished disk that is preformed for registration
15 when a plurality of such disks are nested and for registration with machine parts in bottle capping machinery and for registration with the heads of bottles preparatory to the folding of such disks to complete hood cap form thereon.
20 A further object of the invention is to produce a pre-formed approximately flat slightly-dished hood capping disk of sheet paper like material or of other more or less flexible or resilient non-metallic material, of the self-secur ing or so-called plastic type by reason of a binder carried thereby or by reason of characteristics of the material of which the disk is composed, whereby the disk, or at least the skirt forming portion thereof, is normally set at atmospheric or room temperatures or conditions and is capable of becoming temporarily moldable or tacky when subjected to certain conditions or treatment for quick application to and molding or shaping to final self-secur ing hood cap form on the bottle head
25 and of quickly setting in such form to secured condition on the bottle head, all with the end in view of producing such a disk in such pre-formed shape as to facilitate the operation of hood capping machinery in accurately applying such pre-formed disks to bottle heads and completing the hood capping operations on the bottle heads.

A further object of the invention is to provide as an article of manufacture and sale, a hood capping disk of suitable more or less resilient sheet material, that is more or less slightly dished from the flat plane form and centrally embossed or domed to centrally seat down on the annular top edge or lip of the bottle, as distinguished from a closure originally manufactured in and of complete hood cap form, with the ends in view of gaining space economy in packing and shipping, simplifying disk manufacture, maintaining registration of the disks during machine manipulation, assuring and maintaining bottle and disk registration and centering when the disks and

bottle heads are brought together, and during travel of the bottles with the disks loosely seated thereon, and during shaping of the disks into hood caps and to secured form on the bottle heads.

With the foregoing and other objects in view, the invention consists in certain novel features in structure and formation, as more fully and particularly explained and specified hereinafter.

Referring to the accompanying drawing form- 10 ing a part hereof:

Fig. 1 is a side or edge elevation of a completed pre-formed disk in accordance with the instant invention, for ultimate completion to hood cap form on the bottle head.

Fig. 2 shows said disk in cross section.

Fig. 3 shows said disk in top plan.

Fig. 4 shows in side elevation a bottle head with the disk of Fig. 1, resting loosely and centered on the annular top lip of said head and covering 20 the bottle mouth, preparatory to the machine operation of folding and shaping the disk to hood cap form secured on and enclosing the bottle head.

Fig. 5 is a side elevation of the bottle head with 25 the finally formed hood cap in secured condition on and covering said head.

The disk shown as an example of an embodiment of the invention, is composed of a single more or less flexible resilient sheet having inherent characteristics or an added binder, whereby the disk is rendered plastic or self-secur ing as a finally formed complete hood cap. This disk is slightly dished and otherwise shaped to provide the slightly depressed radially-wide annular skirt forming portion 1, having longitudinal or approximately radial pairs of outwardly diverging creases, bending or fold lines 1a, permanently pressed therein, and the permanent central upwardly embossed dome that is preferably imperforate and flat at the central top 2, joined to said depressed creased annular skirt forming portion 1, by annular downwardly and outwardly curving or slightly downwardly flaring wall portion 2a. The wide annular skirt forming portion 1, is in the example shown although the invention is not so limited, of radially corrugated or step-like formation, by reason of the partially formed tucks and creases or bend lines forcibly pressed therein in the method of 30 manufacturing the disks, to initiate the bending of this skirt formation into the desired folds, gathers and/or tucks to take up the surplus skirt material when the skirt portion is folded and gathered downwardly and inwardly on the bottle 35 40 45 50 55

head to complete long skirted hood cap form and then contracted to the bottle head and neck and pressed inwardly under the bottle head rim to flatten out and compress all of the surplus material tucks and gathers, to the final hood cap 5 securing form and condition, as shown by the drawing illustration of an example of a bottle hood capped by the disk example illustrated.

The disk illustrated is by means of proper dies 10 and pressure, pressed and/or drawn from a plane flat circular disk of more or less resilient sheet paper or other non-metallic flexible and/or resilient sheet material, suitable for hood capping purposes. The annular skirt forming portion 1, is drawn or pressed downwardly from the plane 15 of the flat circular blank, and the upwardly contracting circular central dome 2, is embossed upwardly from the plane of the flat circular blank, usually by separate steps or operations.

The permanent upwardly embossed center dome has a top wall 2, of a diameter to close or 20 cover the mouth of the bottle to be hood capped thereby and the annular top edge or lip of the bottle that surrounds said mouth, and the downwardly curving or flaring annular surrounding 25 upstanding or edge wall 2a, of the dome is preformed to a predetermined internal diameter to receive and freely drop down around the annular outer circumference of the mouth wall of the 30 standard bottle mouth lip and extend down around the same the distance permitted by the vertical depth of the dome and thereby center the disk on the bottle head with the annular upright wall 2a, of the dome depending around the 35 exterior rim of said head to maintain the disk in horizontal position on the head while the bottle, carrying the horizontal disk loosely fitting its head, moves to the hood capping position at which a mechanical folding or molding head performs the operation of folding and gathering the 40 outstanding horizontal skirt portion 1, down to hood cap form on the bottle head and presses the same inwardly and flattens down the overlying folds or tucks and thus holds them until set to securing position on the bottle head.

The approximately flat but usually slightly 45 downwardly directed or flaring annular preliminarily creased or partially or initially folded annular portion 1, is of substantial radial width or 50 diameter and projects outwardly substantially horizontally or transversely to the longitudinal or vertical axis of the domed center 2, 2a, of the disk. This annular portion 1, plus the substantially vertical length of annular depending wall 55 2a, provides material of sufficient length to form the required long depending enclosing and securing annular skirt of the hood cap that is finally completed, from the disk, on the bottle head.

The wide almost horizontal projecting annular portion 1, of the disk is in the process of manufacture, preferably, permanently creased and radially bent, by forcing a flat circular sheet blank through dies to temporary complete flat top approximately cylindrical hood cap form with the 65 surplus material of the annular skirt taken up by tucks or folds of triangular or upwardly converging form that are temporarily folded flat in the dies, without the application of the necessary force and pressure to permanently reduce 70 and compress the sheet material and folds of the skirt to produce the skirt of permanent cylindrical or long form.

The sheet material is of such resiliency and 75 under such tendency to return to its original

flat form, the pressure applied not being sufficient to wholly destroy such resiliency and tendency, that when the disk is released from such dies, the skirt portion springs back to slightly depressed or flaring form with, however, the fold 5 or crease lines and the partially flattened out trucks or folds, permanently remaining, and resulting in the irregular formation of the annular portion 1, designed to cause said portion 1, when a bottle head having the disk 2, 2a, 1, 1a, 10 seated loosely thereon is forced upwardly into a closing or capping head, to fold down to encircling contracted elongated-skirt hood cap form naturally following the fold lines originally impressed in portion 1, and in the completion 15 of the tucks or folds originally initiated or partially formed in said portion 1.

However, we do not wish to limit our invention to any particular initiated folding formation of annular portion 1, nor to the particular forma- 20 tion shown.

In the manufacture of our disks, from flat sheet blanks, the blanks, are, preferably, by a suitable die or pressing operation, for instance, such as hereinbefore described, reduced to a form 25 having a flat circular top or center and a creased annular skirt portion flaring downwardly from the plane of the flat blank or of the flat center.

Then, if not previously formed, the flat center and the annular surrounding radially narrow upper or base portion of said skirt are permanently domed by being embossed, drawn, or forced upwardly from the plane of the original flat blank, say for a distance of five sixteenths of an inch more or less, without intending to limit our invention to any such dimensions. This embossing operation is performed under heavy pressure and by the use of the necessary dies to produce the disk with a permanent dome, approximately such as hereinbefore described, to exteriorly fit over 40 and extend for a short distance down on the bottle head, and a portion of the radial width of the original radially-creased blank skirt is included in this dome, and the exterior or over all diameter of the flared flat center blank is 45 thereby slightly decreased, and also the flare or taper of the skirt of the first dished blank, is somewhat flattened out, by the embossing or doming operation.

This embossing or doming operation can, if 50 so desired, be performed by a cylindrical more or less high pressure reciprocatory embossing ram having a flat working end face of approximately the diameter of the flat center 2.

A fixed circular female die cooperates with and 55 receives this ram. This female die is of an internal diameter but slightly in excess of the diameter of the disk center 2, and said die can be provided with a flat bottom face to oppose the flat end face of the ram in gripping the center 60 2, of the dome of the disk.

When the ram is elevated from the female die, the flat center of the flaring blank is placed under the ram and centered over said female die, and the annular flaring skirt of the blank is clamped 65 and flattened out horizontally by annular clamping means concentrically surrounding the ram and die while the ram descends on the center 2, of the blank and carries the same down through the female die and tightly against the bottom 70 of the die that corresponds in form to the bottom end face of the ram. This descending action of the ram draws down to cylindrical form within the die and around the ram and compresses and smooths out the sheet material thereof, the

annular creased base portion of the previously formed flared skirt of the blank, to form the annular surrounding edge wall 2a, of the dome of the completed disk.

- 5 When the disk with its dome thus drawn or embossed, is ejected from the female die after withdrawal of the ram, and release from the annular clamping surfaces or members, the sheet material of the disk by reason of its natural 10 resiliency and tendency to return to its original flat form, springs or returns to the form approximately as shown with the annular upstanding edge wall 2a, of the upwardly-projecting dome slightly flaring or enlarging downwardly and with 15 the annular depressed skirt projecting outwardly almost horizontally and still irregular or somewhat stepped in form because of the initiated tucks or folds and permanently formed fold lines or creases.
- 20 We do not wish, however, to limit our invention to any particular method or method steps, that may or may not be followed in the production of the article hereof.

While the disk of our invention is primarily 25 intended for plastic or self securing hood capping, say, broadly, as generally outlined, for instance, by the Wilbur L. Wright Patent No. 1,657,950, Jan. 31, 1928, and/or Wright and Pierce Patents Nos. 1,857,073, 1,857,075, May 3, 1932, 30 among others, yet we do not wish to limit all features of our invention to plastic or self securing hood capping, nor to the disk of our invention rendered plastic or self securing by an added binder. The disk of our invention can be composed of non-binder carrying, non-metallic flexible or somewhat resilient sheet material that by reason of its own peculiar composition and inherent characteristics renders the disks of this invention capable of successful use in plastic or 35 self securing hood capping, by conditioning the disk and/or its skirt during the hood capping method, to render the same temporarily self securing and capable of quickly setting to fixed secured form and condition.

45 Where the disks of our invention, to be used for plastic hood capping, are composed of sheet paper material that has not been previously impregnated or otherwise supplied with a suitable binder in quantity to render the disks capable 50 of use in plastic or self securing hood capping, we provide the disks throughout or merely the skirt portions thereof, with the required quantity of any suitable binder, by impregnation through 55 application of the binder to the disks, while in a fused liquid condition. The fused binder is internally taken up by the paper and quickly sets and solidifies therein at atmospheric and/or room temperatures, so that the impregnated disks 60 when shipped from the factory to the bottlers, are in a more or less hard stiff condition, for conditioning in the hood capping machinery to the temporarily soft or moldable condition in which the disks are dispensed onto the bottle 65 heads and then molded to secured hood capping condition thereon.

We have discovered that material advantages and economies are attained, where the manufactured disk for hood capping purposes is maintained with minimum flare and length and consequently as nearly flat and of maximum over all diameter as is possible without forfeiting desirable ease and accuracy in folding or molding on the bottle head and proper registration of the disks when nested, when passing through capping machinery and in application to and trans-

portation on the bottle, as well as when being molded or folded to the desired final hood cap form on the bottle.

The disks are as remote from real hood cap form as it is possible to make them, in that they are of maximum relatively large diameter for ultimate hood capping, are relatively flat or of minimum axial or longitudinal length, with the skirt so flattened out as to be almost or approximately horizontal.

10 These substantially flat disks can be conveyed and handled by machinery with accuracy, speed and economy, and can be quickly and accurately advanced and rotated when arranged edgewise for binder application and conditioning before 15 and after binder impregnation and the binder carrying disks can likewise be economically handled for conditioning in the hood-capping machinery, and also this flat disk with the dome center provides an internal shoulder for engagement by an advancing bottle when wiping the inclined disk from a holder with accurate deposit and centering of the disk in a horizontal position on the bottle head. The flat disks take up 20 minimum packing space when arranged in a 25 stack with their domes nested, and disks are accurately centered or caused to register by the nesting domes, and the machinery for handling and hood capping with said disks is materially simplified and rendered more certain and accurate in operation, by the substantially flat large 30 diameter disk form stiffened as they are by their domed central portions.

25 We do not wish to limit all features of our invention to the initial preforming of the radially 35 wide substantially horizontal marginal portion 1, to cause the surplus material therein to fold along predetermined lines when contracted to long-skirted longitudinal hood cap form, nor do 40 we wish to strictly limit ourselves to the explanatory and illustrative disclosure hereof.

30 What we claim is:—

1. A hood capping element formed of non-metallic sheet material, having an elevated center to cover the bottle mouth and rest on the 45 top surrounding lip thereof and an annular edge wall flaring down from said center to depend around said lip, and a slightly-dished, radially-wide hood-cap-skirt-forming annular marginal portion projecting outwardly from said edge wall. 50

2. A hood capping element substantially circular in shape and formed of non-metallic sheet material, having a central interiorly-unobstructed, open-bottom upwardly-projecting dome to center the element on a bottle mouth covering 55 said mouth and depending down around the annular lip thereof, and an approximately-flat, radially-wide surrounding annular margin projecting outwardly from the annular depending wall of said dome and forming a laterally-extending continuation thereof, said annular laterally-projecting margin being preformed for 60 folding along predetermined lines when drawn downwardly to hood skirt form on the bottle head and pressed inwardly thereon. 65

3. A hood capping element formed of paper material, having an upstanding open-bottom dome with an elevated top wall, and a slightly-dished annular unbroken margin surrounding the base of the annular depending side wall of said dome and projecting outwardly and laterally therefrom, said margin having preformed partial or initiated upwardly and downwardly deflected folds, said element being sufficiently stiff, flat and circular in form to permit rotation and 70 75

advancement thereof by conveying machinery, and wiping thereof from capping machinery onto an advancing bottle head by the engagement of the bottle lip with the inner surface of the dome side wall, and for close nesting for packing and capping machine feeding, and for accurate registration in machinery for handling said element.

4. A hood capping element formed of paper material carrying a binder for securing the folds thereof when contracted downwardly on a bottle head to hood cap form, said element having an upstanding, open-bottom dome with an elevated top wall and an annular downwardly flaring side wall, and a widely-flaring annular margin surrounding and constituting an outwardly and laterally-projecting continuation of

said side wall, said margin having preformed partial fold portions extending approximately throughout the radial width thereof.

5. A hood capping element of substantially resilient sheet material, having an elevated central dome to cover the bottle mouth and rest on the top surrounding lip thereof with an annular edge wall flaring downwardly to depend around said lip, and a slightly-dished radially-wide hood-cap-skirt-forming annular margin projecting outwardly from the base of said wall, said margin being provided with preformed fold lines that meet said wall and extend therefrom outwardly of said margin.
